UNITED STATES PATENT OFFICE

GEORGE LEROY JESSUP, OF WOODLAND, CALIFORNIA

SIGN

Application filed March 18, 1932. Serial No. 599,734.

The invention relates to signs, and has for its object to provide a device of this character having means for supporting letter plates and frames for said letter plates, hingedly connected to the sign and adapted, when in operative position, to engage the edges of the letter plates, hold them in position and at the same time form an ornamental border for the indicia on the letter plates.

A further object is to provide the frames with hinged connections to the sign and to form the frames from channelled members having inner and outer flanges, the inner flanges being positioned to engage the letter plates and the outer flanges to engage the sign around the letter plates and spring means cooperating with the frames and disposed within the channels thereof for forcing the frames to closed position.

A further object is to anchor one of the arms of the springs in the channels and to extend the other arms of the springs through the sign and into engagement with the rear side of the sign.

A further object is to form the hinged connection of the frames to the sign by tongues extending through slots in the sign and having a rocking engagement in the slots.

A further object is to provide the sign with struck out angular shaped lugs for receiving the letter plates, and to position said lugs where they will be received within the channels of the frames and be concealed from view.

A further object is to form the sign, which is of the easel type, with hinged supports having inturned flanges for the reception of a receptacle for letter plates, and to mount the receptacle whereby it is utilized as a brace and stiffening means for the lower end of the sign.

With the above and other objects in view the invention resides in the combination and arrangement of parts as hereinafter set forth, shown in the drawings, described and claimed, it being understood that changes in the precise embodiment of the invention may be made within scope of what is claimed

without departing from the spirit of the invention.

In the drawings:

Figure 1 is a perspective view of the sign. 55

Figure 2 is a side elevation.

Figure 3 is a horizontal sectional view taken on line 3—3 of Figure 2.

Figure 4 is a detail rear perspective view of one of the lower ends of the sign.

Figure 5 is a view in elevation of one of the letter plate frames.

Figure 6 is a vertical transverse sectional view taken on line 6—6 of Figure 5.

Figure 7 is a detail perspective view of a portion of one of the letter frames showing 65 the same from the rear.

Figure 8 is a view in elevation of a portion of the sign, showing the letter plate holding lugs.

Figure 9 is a horizontal sectional view 70 taken on line 9—9 of Figure 5.

Referring to the drawings, the numeral 1 designates the front side of the sign which is provided with a depression 2 for stiffening purposes. The sign is of the easel type 75 and is provided with rearwardly extending hinged side members 3. Extending rearwardly from the rear side of the body 1 of the sign is a horizontally disposed flange 4 and extending inwardly from the sides 3 80 are flanges 5 in the plane of the flange 4, and on which a receptacle 6 is placed and secured for the reception of the letter plates 7. The receptacle 6, when secured in place and to the flanges 5 and 4, stiffens the sign structure as a whole, and adds weight to the lower portion of the sign. The rear flanges 5 are bent inwardly from the angularly shaped members 8 carried by the rear edges of the sides 3, and it will be seen that 85 the member 8 additionally brace the supporting portions of the sign. All of the sign body with the exception of its sides 3, flanges 4 and 5, and members 8, is stamped from a single sheet of material, which is 90 then bent to form, thereby allowing the device to be cheaply manufactured and sold.

The sign body 1 is provided with struck-out angularly shaped lugs 9, which receive the letter plates 7, which may have any in- 100

dicia desired thereon, and hold said plates in position while being assembled on the sign. After the letter plates 7 are properly positioned on the sign body, the letter frames 10 cover the same. The letter frames 10 are formed from channels having inner flanges 11 and outer flanges 12. The inner flanges 11 are narrower than the flanges 12, and when the frames are in closed position engage the letter plates 7 to the inside of the lugs 9, thereby concealing said lugs within the channels, and at the same time forming a uniform ornamental outline for indicia on the letter plates. It is to be understood that the letter frames may be of any size desired, for instance for covering a single letter or figure, or a plurality of letters or figures. The lower sides of the frames 10 are provided with downwardly extending flanges 13, angularly shaped and which flanges are carried by the flanges 12 of the frames and are rockably mounted in slots 14 in the plate 1, so that the frames may be hinged downwardly to allow access to the letter plates 7 when desired. Disposed within the channels of the frames 10 are coiled springs 15, which springs are provided with upwardly extending arms 16 within the channels, and anchored at 17 to the frames; the other arms 18 of the springs extend through the sign body 1, and upwardly into engagement with the rear side of the sign body. It will be seen that the springs and arms are entirely concealed from view from the front of the sign and that they will act on the frames for moving the same to closed position as shown in Figure 6 when released. By providing the coils 15 in the springs, a wide range of flexibility is provided which allows a hinging movement of the frames in the slots 14.

From the above it will be seen that a sign is provided which is simple in construction, particularly adapted for the reception of letter plates, thereby allowing change of indicia, and hinged frames are provided which not only hold the letter plates but receive in channels thereof the letter plate holding lugs and the springs for moving said frames to closed position.

The invention having been set forth what is claimed as new and useful is:

1. An easel sign comprising an indicia carrying member, right angularly disposed side members carried by the indicia carrying member, inwardly extending flanges carried by the side and indicia carrying member in the same plane and a receptacle between the side members and secured to the flanges of the side and indicia carrying members and forming means for bracing the sign and maintaining the parts in relative relation to each other.
2. The combination with the lower end of an easel sign formed from a single sheet of

metal bent to form and comprising front and end members, said front and end members being recessed to form supporting legs, of inwardly struck flanges in the bottoms of the recesses of the front and end members and in the same plane, inwardly turned flanges carried by the edges of the end members, horizontally disposed flanges carried by said inwardly turned flanges and in the plane of the first mentioned flanges and a member secured on said inwardly turned flanges and forming means for maintaining a rigid sign structure.

3. The combination with a sign, letter plate supporting means extending outwardly from one side of the sign, letter plates supported on said letter plate supporting means, of hinged frames carried by said sign, said frames being formed from channelled members having inner and outer flanges, a hinged connection between the outer flange and the sign, the inner flange being narrower than the outer flange and engaging the letter plate when the frame is closed, said frames housing the plate supporting lugs and spring means within the channel of the frame and entirely concealed therein for normally forcing the frame toward closed position.

4. The combination with a sign having letter plates supported thereon, of frames for said plates, said frames being formed from channelled members, said channelled members being hingedly connected to the sign adjacent the plates, of springs entirely concealed within the channelled members, and anchored to the channelled member and sign and forming means whereby the letter plate frames are normally forced towards the sign and letter plates.

5. A device as set forth in claim 4 wherein the springs are U-shaped thereby forming arms, said arms being anchored to the frames and the sign.

6. A device as set forth in claim 4 wherein said springs are U-shaped, the arms of said U-shaped springs being anchored to the frames and to the sign and spring convolutions connecting the arms of the U-shaped springs together.

In testimony whereof he hereunto affixes his signature.

GEORGE LEROY JESSUP.
